UNITED STATES PATENT OFFICE

FRANK DITCHFIELD, OF CLEVELAND, OHIO, ASSIGNOR TO THE YOUNGSTOWN STEEL DOOR CO., OF CLEVELAND, OHIO, A CORPORATION OF OHIO

CAR

Application filed May 12, 1928. Serial No. 277,209.

This invention relates to improvements in an inside elevational view of the improved car wall structure showing more particularly one of the posts and means of attachment to the panels and car framing members. Fig. 4

5 is a vertical sectional view corresponding to the line 4—4 of Fig. 1, Figs. 4 and 5 being upon an enlarged scale and parts being broken away to better accommodate the views on the sheet. Fig. 5 is an enlarged horizontal detail sectional view corresponding to the 60 line 5—5 of Fig. 1. Figs. 6, 7 and 8 are views illustrating a modified form of my invention, Fig. 6 being an inside elevational view, Fig. 7 a vertical sectional view on the line 7—7 of Fig. 6, and Fig. 8 a horizontal 65 sectional view on the line 8—8 of Fig. 6. Figs. 9, 10 and 11 are views illustrating another modification of the invention, Fig. 9 being an inside elevational view, Fig. 10 a vertical sectional view on the line 10—10 of 70 Fig. 9 and Fig. 11 a horizontal sectional view on the line 11—11 of Fig. 9. Figs. 12, 13, 14 and 15 are views illustrating still another modification, Fig. 12 being an inside elevation view, Fig. 13 a vertical sectional view on 75 the line 13—13 of Fig. 12, and Figs. 14 and 15 being horizontal sectional views on the lines 14—14 and 15—15, respectively, of Fig. 13.

Another object of my invention is to provide a car wall structure composed of sheet metal panels and metal posts, the latter being formed or rolled and so associated with the panel sheets that the vertical lap joints of the latter lie against and are secured to vertical webs of the posts to thus obtain a strong 80 union of the parts, the panel sheets being uniformly corrugated or integrally braced between the posts.

Still another object of my invention is to provide, in a car sheet metal wall arrangement 85 having posts associated therewith, strong, substantial and relatively inexpensive means for attaching the upper and lower ends of the posts to the adjacent car sills and end or side plates.

40 Other and more specific objects of the invention will more clearly appear from the description and claims hereinafter following.

In the drawings forming a part of this specification, Fig. 1 is a side elevational view 45 of a portion of a box car side showing my improvements incorporated therein. In this view, the car wall is shown from the end to the nearest usual side door post. Fig. 2 is a horizontal sectional view on the line 2—2 of Fig. 1 upon an enlarged scale. Fig. 3 is

Referring first to the construction illustrated in Figs. 1 to 5, inclusive, the car side sill is indicated at 20, the side plate at 30 and the panels are each indicated generally by the reference character 40. The posts are designated generally by the reference character 50.

The side sill will generally be a channel having a vertically extending web or section 21 and a horizontal inwardly extending top flange or section 22. The top side plate 30 is shown in the form of a Z-bar having an inner vertically extending flange 31, a horizontally extending web or section 32 and a depending outer flange 33.

The sheet metal panels 40 are preferably 95 of like construction except for minor variations that may occur on those panel sheets at the ends where united to the car corner post 70 and the side door post 71. Each panel will preferably be of a length corresponding 100

to the distance between the side plate and side sill, the width of the panels being made to suit. Each panel has a lower relatively wide flat marginal portion 41 extended down-
 5 wardly over the web 21 of the side sill, said marginal portions being secured to the side sill by a series of rivets 72. The panels also have top, somewhat narrower flat marginal portions 42, which lie against the inner face
 10 of the depending flange 33 of the side plate, said top marginal portions being secured to the side plate by a series of rivets 73. Intermediate the tops and bottoms of the panels, the latter are provided with a series of
 15 inwardly offset corrugations or indentations 43, each of the latter, as shown, having a flat rectangular bottom 44, upper and lower inwardly converging walls 45—45 and inwardly converging end walls 46—46. The panels
 20 are thus supported, horizontally, by what approximate reverse corrugations 47 which are appreciably narrower, as shown in Fig. 4.
 The adjacent vertical edges of each pair of panels have flat margins 48—48 which are
 25 overlapped and riveted together, as indicated in Fig. 5, by a line of rivets 74, said rivets also uniting the overlapped edges of the panels to the central web 51 of the corresponding vertical post.
 30 The post 50 may be said to be of double U-cross section, as best indicated in Figs. 2 and 5, and in addition to the main outer central web 51, has vertically extending webs 52 extending inwardly therefrom, at right
 35 angles. At the inner ends of the webs 52, the metal is thence extended in opposite directions to provide webs 53—53 arranged parallel to the car side, the latter in turn being bent outwardly so as to provide still further
 40 webs 54—54 arranged perpendicular to the car side and the latter terminate in flanges 55—55 which are secured by vertical lines of rivets 75—75 to each of the inwardly offset corrugations 43 of the panels at each side of
 45 the post.

Referring to Fig. 5, it will be noted that the webs 52 are of approximately twice the width of the webs 54 so that the longitudinally extending webs or sections 53 are in-
 50 wardly offset from the bottoms of the corrugations a distance approximately the same as the depth of the corrugations. It will further be observed that a very rigid tubular construction is thus formed between each
 55 panel sheet and corresponding adjacent half of the post, this tubular construction comprising the portions 52, 53 and 54 of the post and the series of inclined end walls 46 of the corrugations. This arrangement is ex-
 60 ceedingly strong and well adapted to resist stresses in any direction and particularly are the panel sheets braced against collapse from blows applied thereto in a horizontal plane from any direction. Vertically, the panel
 65 sheets are greatly strengthened, inasmuch as

the post is connected to the bottoms of the corrugations and forms a bridging piece therebetween, thus preventing the latter from yielding under any vertical stress. It will further be observed that the post provides an inwardly facing open channel adapted for the reception of a wood nailing strip, indicated by dotted lines in Fig. 5 and referenced 70
 76. The inner face of the latter will be flush with the sections 53 of the post and the inner sheathing applied thereto, there thus being left a proper space between the sheathing and the corrugated sheets for the usual battens 75 on the outer side of the sheathing.

The bottoms of the posts are rigidly attached to the side sill by base or attaching plates 60. Each of the latter has a main bottom flange 61 by which the plate is secured to the flange 22 of the side sill by a plurality of rivets 77. Said flange 61 is extended inwardly beyond the sill flange 22 as shown in Fig. 4, so as to provide an ample toe-hold or support for the floor boards which come opposite the post. The floor boards at either side of the post of course have ample support on the flange 22 of the side sill. Said base plate 60 also has two complementary vertically extending flanges 62—62, each being formed to fit against the sections 52, 53 and 55 of the post, as best shown in Fig. 5. Each said flange 62 is riveted to the post by a rivet 78 and the lowermost rivet of the series 75 is also utilized for this purpose. The flanges 62 terminate within the wood nailing strip pocket so as to leave the space for the latter 100 clear.

The upper end of each post is secured to the side plate 30 by a similar base or attaching plate 160, the only difference being that the latter does not have as wide a flange as the flange 61 used at the lower ends of the posts.

With the construction described, it will be seen that the posts may be made of relatively light gauge metal, while at the same time obtaining great vertical column strength, thereby preventing buckling under any ordinary conditions. Further, the means of attachment to the side sill and side plate are such as to practically eliminate any possibility of the post tilting out of the vertical with respect to either the side sill or side plate, either transversely of the car or in a plane lengthwise thereof, thus eliminating or minimizing the possibility of weaving or warping of the superstructure. The horizontal corrugations in the panel sheets obviously brace not only the sheets themselves but the posts, one with another, and the corrugations serve to prevent shimming or vibrating of the panel sheets, a difficulty heretofore experienced in certain types of box cars having sheet metal walls. The panel sheet arrangement is manifestly such that the same can be readily manufactured and the sheets assembled with the posts and a complete unit for 110
 115
 120
 125
 130

one-half of the car side readily applied to the car side sill and side plate, it only being necessary to apply the lines of rivets 72 and 73 and the rivets which secure the plates 60 and 160 to the side sill and side plate, thus minimizing the cost of manufacture and assembling.

Referring to the construction illustrated in Figs. 6, 7 and 8, the sheet metal panels 140 are the same as in the first described construction and said panel sheets are attached to the side sill 120 and the side plate 130 in the same manner. In this modification, the post 150 is made of single U-cross section, as shown in Fig. 8, the same having a main bottom or outer web 151 secured to the overlapped vertical edges of the panels by the vertical series of rivets 174. The post also has side arms 152—152 and oppositely extended inner flanges 155—155. The same open channel formation for the reception of a wood nailing strip is provided as in the first construction.

In this form of the invention, the posts 150 are secured at their lower ends to the side sill by a T-shaped base plate or casting 160', the latter having a lower horizontal flange 161 and a vertically extending flange 162. The latter is secured to the flanges 155 of the post by rivets 175 and the bottom flange 160' is secured to the top flange 122 of the side sill by rivets 177.

The top end of each post 150 is secured to the side plate by a somewhat similar attaching plate, the same having a depending vertical flange 163 riveted to the flanges 155 of the post, a horizontal flange 164 riveted to the web of the side plate 120, and a vertically extending flange 165 riveted to the vertical inner flange of the side plate.

Referring next to the construction shown in Figs. 9, 10 and 11, the arrangement of panels 240 and posts 250 is the same as that shown in Figs. 6, 7 and 8. The only difference is in the face of attaching plates for the posts. The base plate 260 has a horizontal bottom flange 261 riveted to the top flange 222 of the side sill, and a vertically extending flange 262 which extends from end to end of the base plate as shown in Fig. 11.

The flange 262 is offset intermediate its ends as indicated at 263—263, where it is riveted to the flanges 255 of the post, as by rivets 275. The upper attaching plate is similar to the lower, except that it has an additional upturned flange 264 riveted to the inner vertical flange of the side plate 230.

Referring next to the construction illustrated in Figs. 12 to 15, the sheet-metal panels 340—340 are the same as in the first described form and said panels have their direct attachments to the side sill 320 and side plate 330 in the same manner.

The posts 350 are substantially the same as the posts 50 of the first described construc-

tion, the only substantial difference being that each post 350 is necked-in at its bottom and top ends below and above the lowermost and uppermost horizontal corrugations of the panel sheets, respectively. Where the post 350 is necked-in, the sections 352, and 354 which extend perpendicularly to the side wall of the car are all of the same depth and of lesser depth than the depth of the corrugations in the panel, as clearly indicated in Figs. 14 and 15, although the general contour of a cross section of the post remains the same, as will be evident.

The necked-in upper and lower ends of the post are secured to the side sill and side plate by base or attaching plates 360, similar to the base plates 60, each said plate 360 having a bottom horizontal flange 361 and a vertically extending flange 362, the latter conforming throughout its length to the contour of the necked-in portion of the post. The attaching or base plate 360 is riveted to the upper flange 322 of the side sill. By necking-in the post at the bottom thereof, it is unnecessary to extend the base flange 361 of the attaching plate.

Although I have herein shown and described my improvements with particular reference to the side wall of a box car, nevertheless, I am aware that the improvements may be equally well employed in the end wall structure of a box car and also that many features of the improvements may be employed with beneficial effect in wall structures of other types of cars without departure from the spirit of my invention. All changes, modifications and variations are contemplated that come within the scope of the claims appended hereto.

I claim:

1. In a car wall, the combination with a sill; of wall-forming metal sheets secured at their lower ends to said sill; and a vertically extending element having a flat centrally disposed section and other sections at right angles thereto, the adjacent vertical edges of the sheets being overlapped and secured to the outer face of said central section, said element being disposed on the inner side of said sheets.

2. In a car wall, the combination with a sill; of a top plate; wall-forming metal sheets secured at their upper and lower ends to said plate and sill; and a post having a flat centrally disposed section and other sections at right angles thereto, the adjacent vertical edges of said sheets being overlapped on the outer side of and secured to the central section of the post, said post being disposed on the inner side of said sheets.

3. In a car wall, the combination with a side sill having a top horizontal flange; of a side plate; wall-forming metal sheets secured at their upper and lower ends to said side plate and side sill; and a vertically ex-

tending post on the inner side of said sheets secured at its upper and lower ends to said plate and said top flange of the sill, said post having a centrally disposed flat outer section, the adjacent vertical edges of the sheets being overlapped on the outer side of and secured to said central section of the post.

4. In a car wall, the combination with a sill; of wall-forming sheets having horizontally extending corrugations therein and secured at their lower ends to said sill; a post secured to the inner side of the wall and having portions united with some of said corrugations, said post having a vertically extending recess formed therein opening inwardly and adapted for the reception of a nailing strip; and means for securing the lower end of said post to the sill.

5. In a car wall structure, the combination with a sill; of a top plate; metal sheets extending between and secured to said sill and plate; posts on the inner sides of said sheets, said posts being of the same cross section from top to bottom; and means securing the bottom of said post to the sill, said means comprising a base plate having a lower horizontal flange secured to the top of the sill and extending inwardly thereof to provide a widened support for floor boards.

30. 6. In car wall construction, the combination with sheet metal panels having strengthening indentations therein disposed to one side of the main plane of the sheets; of a vertically extending framing element on said side of the panels and to which the adjacent edges of the panels are secured, said element having oppositely extending portions overlapping and secured to the indentations of the respective panels.

40. 7. In a car side wall construction, the combination with a side sill; of a side plate; sheet metal panels extending between said sill and plate and secured thereto, said panels having strengthening indentations therein disposed to one side of the main plane of the sheets; and a post extending between said sill and plate, said post being disposed on the side of the panels to which the indentations are extended and having the edges of the panels secured thereto, said post having oppositely extending portions overlapping and secured to the indentations of the respective panels.

8. In car wall construction, the combination with wall-forming sheet metal panels having strengthening indentations therein pressed inwardly of the panels; a vertical framing element on the inner side of said panels and to which the adjacent edges thereof are secured, said element having oppositely extending portions overlapping and secured to the crests of said indentations.

9. In a car side wall construction, the combination with a side sill and side plate; of a plurality of sheet metal panels extending between said sill and plate and secured thereto,

said panels having integrally formed indentations pressed inwardly therefrom; of posts extending between said sill and plate and secured thereto, each post having the vertical edges of two adjacent panels secured thereto, said posts being disposed on the inner sides of the panels and each having oppositely extending flanges overlapping and secured to the crests of the indentations of the respective adjacent panels.

10. In a car wall construction, the combination with a sill; of wall-forming sheet metal panels united along their vertical edges and provided with horizontally disposed corrugations terminating intermediate the vertical edges of the panels; a vertically disposed framing element secured to said panels intermediate said corrugations; and rigidifying means extending from said element to said corrugations and secured to both said element and the crests of the corrugations.

11. In a car side wall, the combination with a side sill and side plate; of a plurality of sheet metal panels secured at their top and bottom portions to said plate and sill, adjacent vertical edges of said panels being united and each panel provided with horizontally disposed corrugations, the latter being disposed inwardly; and a post at each of the overlapped joints of the panels, each post having integral means extending over the crests of the horizontal corrugations and secured thereto.

12. In a car wall construction, the combination with a sill; of wall-forming sheet metal panels united along adjacent vertical edges, each of said panels having a plurality of corrugations pressed inwardly therefrom; and a post, the latter being of double U-cross section with oppositely extending flanges, the latter being secured to the crests of said corrugations.

13. In a car side wall, the combination with a side sill and side plate; of a plurality of sheet metal panels attached to said sill and plate, adjacent vertical edges of said panels being overlapped, each panel having horizontally extending corrugations therein; and a sheet metal post at each of the overlapped joints of the panels, each post being of double U-cross section with edge flanges, the latter being secured to the crests of said horizontal corrugations.

14. In a car wall construction, the combination with a sill; of wall-forming metal panels secured to said sill and having strengthening indentations therein; and a formed metal post having flanges secured to said panels, said post having also a U-section opening inwardly for the reception of a nailing strip.

15. In a car side wall, the combination with side sill and side plate; of sheet metal panels secured to said sill and plate, said panels having integrally formed strength-

ening indentations therein; and side posts secured at their upper and lower ends to the plate and sill, each said post having vertically extending flanges secured to the panels and a U-section opening inwardly of the car adapted for the reception of a nailing strip.

16. In a car wall construction, the combination with a sill; of a top plate; sheet metal panels attached at their upper and lower ends to said plate and sill; posts secured to said panels; and an attaching member at each end of the post, each member having a vertically disposed flange secured to sections of the post and a horizontally disposed flange secured to the respective sill or plate.

17. A side wall construction for box cars including: A metal side sill; a metal side plate; a plurality of sheet metal panels secured along their bottom and top edges to said sill and plate, each panel having a plurality of horizontally extending corrugations incorporated therein, said corrugations extending inwardly; a formed post at the joint between each pair of panels, each post having a flat outer section and the corresponding vertical edges of the panels being overlapped and secured thereto, each post having a channel section facing inwardly of the car adapted for the reception of a nailing strip, each post having also means extending from opposite sides thereof overlying and secured to the crests of said corrugations.

18. A side wall construction for box cars including: A metal side sill; a metal side plate; a plurality of sheet metal panels secured along their bottom and top edges to said sill and plate, each panel having a plurality of horizontally extending corrugations incorporated therein, said corrugations extending inwardly; a formed post at the joint between each pair of panels, each post having a flat outer section and the corresponding vertical edges of the panels being overlapped and secured thereto, each post having a channel section facing inwardly of the car adapted for the reception of a nailing strip, each post having also means extending from opposite sides thereof overlying and secured to the crests of said corrugations; and base plates for securing the upper and lower ends of said posts to the side plate and side sill, each base plate including a vertically disposed flange conforming to the contour of the post and secured thereto, and a horizontal flange secured to the corresponding sill or side plate.

19. In a car side wall, the combination with a side sill and a side plate; of a plurality of sheet metal panels attached at their upper and lower portions to said plate and sill, adjacent vertical edges of the panels being united, and each panel having a plurality of horizontally disposed, inwardly offset corrugations therein; and a post at each of the overlapped joints, each post having a

central web section to which the overlapped edges of the panels are secured, each post further having opposed inwardly extending sections, sections extending oppositely and parallel to the side, additional sections extending outwardly, and edge flanges, the latter being riveted to the crests of the horizontal corrugations.

20. In a car wall structure, the combination with a side sill; of a top plate; a plurality of wall-forming metal sheets secured at their upper ends to said top plate, said sheets having vertically extending lapped joints; means securing the lower ends of said sheets to the side sill; and a vertically extending element at each of the lapped joints of the sheets, each said element having a flat centrally disposed section and other sections at right angles thereto, the corresponding lapped joints of the sheets being secured to the outer faces of the central sections of said elements, each of said elements being disposed on the inner side of the sheets.

21. In a wall structure, the combination with horizontally extending top and bottom frame elements constituting part of the wall; of wall-forming metal sheets secured at their upper and lower ends to said elements respectively; and a post extending between and secured at its ends to said elements, said post being disposed on the inner side of the sheets and having a flat, centrally disposed section with other sections at right angles thereto, the adjacent vertical edges of said sheets being overlapped on the outer side of and secured to said central section of the post.

In witness that I claim the foregoing I have hereunto subscribed my name this 31st day of March, 1928.

FRANK DITCHFIELD.
